UNITED STATES PATENT OFFICE.

ALFRED N. NELSEN, OF LONG BEACH, CALIFORNIA.

LIFE-SAVING BOAT.

1,321,541.

Specification of Letters Patent. Patented Nov. 11, 1919.

Application filed January 22, 1917. Serial No. 143,837.

To all whom it may concern:

Be it known that I, ALFRED N. NELSEN, a citizen of the United States, residing at Long Beach, in the county of Los Angeles and State of California, have invented a new and useful Life-Saving Boat, of which the following is a specification.

An object of my invention is to provide a life boat capable of superior service in point of buoyancy, strength, equilibrium and manipulation.

This invention is regarded as broadly new and pioneer in that my life-saving boat comprises a practically flat bottomed hull bounded by upper and lower curved surfaces that extend aslant outwardly from the top and bottom walls of said hull and are joined at the perimeter of the boat and constitute side floats for said hull forming an edge at the rim of the boat between parallel planes extending across the boat at the bottom and top of the hull respectively, the principle being that the sides thus constructed make the boat non-capsizable, said surfaces practically forming fenders to receive and shed the waves.

Another feature is the provision of a central removable air compartment.

Another feature is the provision of removable spray hood compartments adapted to contain food and to serve as tarpaulin supports.

Another feature is the provision of wheels for the hull to run upon the beach.

Another feature is the provision of a horizontal keel board above the level of the wheel bases.

Another feature is the provision of a folding drag or retarder.

Other objects, advantages and features of novelty may appear from the accompanying drawings, the subjoined detail description and the appended claims.

The accompanying drawings illustrate the invention.

Figure 1 is a top plan, partly in section, of a life boat embodying the principles of my invention with only one of the removable spray hoods in place, the other being omitted.

Fig. 2 is a sectional elevation on line α^2 , Fig. 1, with the spray hoods in place.

Fig. 3 is a cross section on line α^3 , Figs. 1 and 2.

Fig. 4 is a fragmental bottom plan view on a reduced scale.

Fig. 5 is a side elevation of the complete boat. Removable spray hoods at both ends are detached and not shown.

Fig. 6 is an enlarged fragmentary sectional elevation.

Fig. 7 is an enlarged cross-sectional detail on line α^7 , Fig. 5.

Fig. 8 is an end elevation viewed from the left of Fig. 5.

The first and most conspicuous feature of the hull 1 of my life boat is the fact that the hull is completely bounded by two curved surfaces, the upper surface 2 and the lower surface 3, meeting at sharp angles and forming a continuous horizontal edge 4, the width of the hull being greater than the depth on any cross-sectional line, and the upper surface being substantially straight longitudinally. A reinforcement 5 is applied to cover the edge 4 all the way around. In side elevation the edge 4 curves upwardly to the ends. The shell or outer frame 6 is shown constructed of wood, but obviously it may be made of sheet metal.

The meeting line or edge 4 of the two curved surfaces is about half way up from the bottom or half way down from the top at any given vertical plane.

By this combination with a practically flat bottomed hull, of the upper and lower slanting surfaces 2, 3, meeting at the rim of the boat intermediate parallel planes that extend respectively across the boat at the bottom and top of the hull and forming floats at the sides of the hull by means of said upper and lower slanting surfaces, the boat is specially adapted to resist capsizing or destructive action of the waves. Any wave striking the sharp edge formed by the junction of the slanting surfaces will either be divided by such sharp edge or will pass under the flat bottom. If the wave is divided between its crest and base, the weight of the crest of the wave is applied to the top surface and counteracts the lifting action of the lower part of the wave. If, on the contrary, the wave strikes only the underside of the surface 3 on the side of the hull the capsizing effect is resisted, first by the buoyancy of the float on the other side of the hull, and second, immediately thereafter, by the base of the wave itself, which passes under the flat bottom.

Furthermore, the slanting under-surface on the side opposite that which receives the impact of the wave meets with the resistance of the water

at a distance from the hull and glides over the water, so that it is practically impossible to capsize the boat in the roughest water.

In other words a boat constructed in accordance with this invention is adapted to coast shoreward broadside on the surf which would inevitably capsize boats of the common construction. Furthermore, the hollow float extensions thus provided for the hull serve as sliding fenders to protect the boat from being stove in.

The inner frame stringer walls 7 and 8 are mounted substantially in vertical positions edgewise and extend from end to end in the hull in straight parallel lines. Actually for convenience and strength these walls are slightly flared outwardly as they proceed upwardly from the bottom.

Cross braces 9, 10, 11, 12, 13 extend outwardly from the walls 7 and 8 to the outer frame or shell 6 at both sides, thus forming compartments for the removable air tight tanks 14, 15, 16, 17, these compartments and tanks being substantially triangular in cross-section; the outer angle and the inner side being practically bisected by the horizontal plane in which the edge 4 lies when the boat is on an even keel. The sections 18, 19 of the outer frame 6 which cover these compartments are made removable to provide access to the tanks, and are held in place by screws 6''. Perforated cross-walls 20 and 21 are inserted between the ends of the stringer walls 7 and 8 near their ends and together therewith and the hulls 1 form compartments to receive the tanks 22 and 23 for fresh water or ballast. The sections 24 and 25 of the outer frame above these tanks are removable. Second cross-walls 26 and 27 are inserted inside of the walls 20 and 21 and form the cock-pit 28 between the walls 26 and 27 and form the kit-rooms 29 and 30 outside of said walls. The carrying wheels 31 extend through the lower shell into the kit-rooms 29 and 30. The central air tank 32 is placed upon the bottom of the cock-pit 28, there being vertical longitudinal walls 33 and 34 upon the sides of this air tank extending from end to end of the cock-pit and a removable cover 35 over the tank secured by screws 35'.

Inside cock pit bottom stringers 33' made of light strong wood about two or more inches thick according to the size of the boat are very solidly secured in place alongside the air tank walls 33, 34 and between the same and the stringer walls 7, 8, and fill the spaces between the bottoms of walls 7 and 33 and 8 and 34; to which walls and the bottom of the shell 6 they are fastened by galvanized iron nails or other suitable fastenings.

Hinged covers 36 and 37 secured by buttons 37' are provided for the kit-rooms. Cleats 38 are fixed crosswise upon the air

tank cover 35 and a strip of canvas 38' extends from end to end over the cleats and is secured in place to form seats for the boatman. The bottoms of the kit-rooms are perforated and the ballast compartments 22 and 23 drain into the kit-rooms and the cock-pit 28 drains through the bottom. Various draining perforations are indicated at a in the several views.

Three parallel runners 39 extend longitudinally of the boat from near the front pair of land wheels 31 to near the rear pair of wheels upon the lower face of the bottom; said runners serving somewhat as a keel and serving to protect the bottom. The keel-board 40 is a heavy sheet metal plate having rounded ends and fixed horizontally below the center of the hull and above the line of the wheel bases so as not to drag on the ground when the hull is on bottom or land and running upon the wheels. The horizontal keel-board 40 is spaced from the boat bottom by the central runner; and its ends and its lateral edges 40' are free to cut the water and to catch thereon to resist capsizing action.

The swinging drag 41 is a plate of heavy sheet metal and is secured to the lower face of the bottom behind the rear wheels by suitable means as staples 42; said staples being long enough to allow a space between the pivoted edge of the folded drag and the boat bottom, so that the drag may cut the water as the boat runs forward and may gather water so as to serve as the keel-board 40 when folded, thus to assist in resisting capsizing forces. A cord 43 is attached to the free end of the drag 41 and passes upwardly through the hull bottom into the kit-room and is attached to the boat, said cord being long enough to allow the drag to swing backwardly to a horizontal position when the cord is let out.

The spray hoods 44 and 45 are removably mounted upon the top sides of the ends of the hull and are substantially alike. The hood bottoms 46 fit the upper surface 2 of the hull beyond the kit-rooms 29 and 30, and hook-shaped flanges 47 extend from the bottoms 46 outwardly around the reinforcement 5 to hold the hoods firmly seated. The hood heads 48 extend upwardly from the inner ends of the bottoms 46 cross-wise of the hulls and the hood covers 49 are secured to the edges of the heads 48 and complete the compartments 50. Manhole constructions 51, which may be closed airtight, provide access to the compartments and when closed, exclude water therefrom. The hoods may be removed by sliding fore and aft, respectively outwardly and may be held in place by bolts, hooks or by eyes 52 or other suitable constructions.

The heaving lines 53 may be stored in the forward kit-rooms and the heaving line-

buoy 54 may be stored upon hooks 55 upon the head 48 of one of the hoods. The buoy may be a pneumatic ring, two or three inches in cross section and fifteen to twenty 5 inches in diameter. This buoy attached to a line may be heaved seventy-five feet, and it weighs two or three pounds.

Hooks 56 are fixed in the kit-rooms to receive ropes or hooks for hanging the life 10 boat in davits on board ship.

The inside cock-pit bottom stringers 33' give great strength and rigidity to the shell and the stringers to which they are fastened. They also assist in giving stability to the 15 boat by adding to the weight in the bottom of the boat evenly balanced on opposite sides of the central longitudinal air chamber. Said stringers are desirably made of red-wood, or other strong wood that is 20 lighter than water and which will be buoyant in water, though heavier than the air compartments alongside and above the level thereof.

The tops of the bottom stringers are flat 25 and the bottoms are trimmed at the ends to fit the shell.

The life boat thus produced has been well tried on the beach and in the breakers. The boat without the hood has been put into 30 a rising comber just as it breaks at its fastest speed, with two men paddling, the bow end projecting about eighteen inches from top of comber or breaker. It can be paddled at any angle into the breaker with- 35 out capsizing. When running broadside with speed or lying calm, the combers break over the boat and it rises immediately without capsizing.

The long shear, straight and flat surface 40 at the bow enables the boat to slide gently and safely without shearing or breaking.

The drag hangs loosely under the stern when the boat is about to come in before the breakers. Pulling the drag cord ten or 45 twelve inches pulls the drag forward and holds the boat until it straightens and then lets go again. The drag may be pulled forward up to the bottom of the boat when going out over the breakers, there being a 50 slight opening between the drag and the bottom of the boat so that the water runs through without much resistance and in this way the drag serves as an additional keel board.

55 The keel board takes the place of a center board and holds the boat steady when under way.

The boat may be equipped with sails, or 60 the double paddles may be used, or it may be provided with machinery, for use on ships, yachts and launches, as well as for use on a beach.

The land wheels are a great advantage for 65 life saving purposes as they allow the boat to be pushed forward easily and gotten

under way so as to dash through breakers. They also serve to allow the boat to be used as an amusement device in connection with an incline, not shown, arranged to direct the boat into the water.

The life lines 57 may be attached at their 70 ends to the ends of the hull and swing alongside. The double bladed paddle 58 may rest upon hooks alongside the cock-pit.

I regard the distinguishing features of 75 the hull as of great importance.

The peculiar construction and shape of the hull well adapts the hull to withstand 80 blows and pressure against the sides or ends. A wave or breaker striking from any direc- 85 tion is cleft horizontally as with a knife. The edge projects beyond the body in every direction and an impact force is evenly divided up and down. This protects the boat in striking the sides of a ship, a dock 90 or the like.

The tarpaulin 59 may be drawn over the 95 top of the hull and engaged by the buttons 60 on the hoods at the ends of the boat so as to give protection to passengers in 100 case of ship wreck at sea.

I claim:

1. A hull, practically flat bottomed, formed by an upper and lower curvilinear shell the edges of which meet at a sharp 95 angle to form an outwardly projecting edge.

2. A hull practically flat-bottomed, formed by an upper and a lower curvilinear shell the edges of which meet at a sharp angle to 100 form an outwardly projecting edge, said hull being substantially wider than its height.

3. A hull practically flat bottomed formed by an upper and lower curvilinear shell the edges of which meet at a sharp angle to 105 form an outwardly projecting edge, said upper shell being substantially straight longitudinally.

4. A hull practically flat bottomed formed by an upper and lower curvilinear shell the edges of which meet at a sharp angle to 110 form an outwardly projecting edge, said meeting line curving upwardly toward the ends.

5. A hull practically flat-bottomed, formed by the combination of an upper and lower curvilinear shell the edges of which meet at a sharp angle to form an outwardly projecting edge, vertical stringer walls between the shells from end to end, and means forming air tight compartments outside the stringer walls.

6. A hull comprising an outer lower curved shell, an outer upper curved shell meeting the lower shell at the perimeter of 125 the boat said shells being spaced from each other at their rims, vertical stringer walls between the spaced recess of said shells from end to end, cross walls between the stringer walls and forming a cockpit, and 130

an air tight compartment extending longitudinally at the transverse center of the cockpit.

7. A hull comprising an outer lower curved shell, an outer upper curved shell meeting the lower curved shell at the perimeter of the boat and spaced apart at their rims, vertical stringer walls between the spaced rims of the shells from end to end, 10 cross walls between the stringer walls and forming a cockpit, and an air tight compartment extending longitudinally at the transverse center of the cockpit, and means forming removable compartments beyond 15 the ends of the cockpit.

8. A hull, and a drag comprising a flat plate centrally hinged to the bottom of the hull on a transverse line.

9. A hull, and a drag comprising a flat plate centrally hinged to the bottom of the hull on a transverse line and means for operating the drag.

10. A hull bounded by two curved surfaces meeting on horizontal planes and a 25 drag comprising a flat plate centrally hinged to the bottom of the hull on a transverse line and means for operating the drag.

11. A hull and a spray hood compartment removably mounted upon the end of the 30 hull the end of said hull extending underneath said spray hood.

12. A hull having a cock-pit, an air tight compartment extending longitudinally in the cock-pit, transverse cleats extending up-

wardly from the compartment, and a strip 35 of canvas extending longitudinally over the cleats and secured to form a series of seats.

13. A hull comprising an outer lower curved shell, an upper curved shell meeting the lower curved shell to form an outwardly 40 projecting edge, vertical stringer walls between the shells from end to end and forming compartments outside of the stringer walls, said compartments being triangular in cross-section, thick wooden inside cock- 45 pit bottom stringers fastened to the shell and spaced to receive between them, an air tank, and extending along and fastened to said stringers.

14. A hull comprising an outer lower curved shell, an outer upper curved shell meeting the lower shell to form an outwardly projecting edge, vertical stringer walls between the shells from end to end, 50 cross walls between the stringer walls and forming a cock-pit, an air tight compartment extending longitudinally at the transverse center of the cock-pit, and inside bottom cock-pit stringers fastened to the floor and to stringer walls and to the walls of the 55 longitudinal air tight compartment walls.

In testimony whereof, I have hereunto set my hand at Los Angeles, California, this 9th day of January, 1917.

ALFRED N. NELSEN.

Witness:

JAMES R. TOWNSEND.
